UNITED STATES PATENT OFFICE

JOHN W. SHEPERDSON, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

OPERATING MECHANISM FOR METAL-CUTTING SHEARS

Application filed May 25, 1929. Serial No. 366,012.

The present invention relates to operating mechanism for metal-cutting shears of the type known as "flying shears", which are employed in steel mills to cut the rapidly moving hot rolled product of the mill into commercial lengths as fast as it is delivered from the finishing rolls.

Such a shearing mechanism, employing a steam-operated piston and cylinder unit for securing the travel of the cooperating shear blades in unison with the stock, so as not to retard the movement of said stock while the successive cuts are taking place, is shown and described, for example, in United States Letters Patent No. 1,521,514 of V. E. Edwards, dated December 30, 1924. In the mechanism of this Edwards patent, after each rapid swing of the cooperating shear blades in the direction of travel of the stock, there is necessarily a relatively slow return movement of the shear frame and its blades back to the normal open or rest position of the shear. That is to say, while the working or cutting swing of the shear is secured with full steam pressure on one side (the upper side) of the shear-actuating piston, accompanied by the free exhaust of steam from the other or lower side of said piston,—it is nevertheless a fact that on the return stroke of the shear actuating piston of this Edwards patent, said piston is subjected to full steam pressure on both sides,—the return movement, under these conditions, occurring only by reason of the fact that the under side of the piston presents a greater effective area than the upper side. Consequently, the return stroke takes place at a relatively slow speed, in the operation of the shear of this Edwards patent.

Such a slow return stroke, which is characteristic of the action of all previous steam-operated flying shear mechanisms, serves well enough when the moving stock is being cut up into relatively long pieces, as such lengths give ample time for the cooperating shear blades, after taking each cut, to return to their normal stationary open positions. But for cutting the moving stock into shorter pieces, or even into longer pieces where the delivery speed of the stock is quite high, such a slow return movement of the flying shear

parts is wholly unsatisfactory, and imposes very serious limitations on the output and operating efficiency of the mill which produces said stock.

The present invention overcomes these difficulties by a construction which relieves the steam pressure on the upper side of the shear-operating piston at or near the end of the cutting stroke, so that its return stroke, for the restoration of the shear blades to normal open position, can take place at any speed desired. Other and further objects and advantages of the invention will be made apparent in the following detailed description thereof, in connection with which reference is had to the accompanying drawings, in which—

Fig. 1 is a general view in side elevation, partly in section, showing a flying shear to which the operating mechanism of my invention is applied.

Fig. 2 is a large scale longitudinal sectional view of the piston and cylinder unit, and associated valve parts, which are employed, according to my invention, for the operation of the shear.

Figs. 3 and 4 are diagrammatic views, similar to Fig. 2, on a smaller scale, showing the parts in different positions.

Figs. 5 and 6 are fragmentary sectional views illustrating the pilot valve construction which may be employed for the actuation of the main steam valve of the piston and cylinder unit, Fig. 5 being a section in the plane of line 5—5, Fig. 2, and Fig. 6 being a larger scale section in the plane of line 6—6, Fig. 5.

Like reference characters refer to like parts in the different figures.

Referring first to Fig. 1, the shearing mechanism proper, which may be of substantially the same type as that shown and described in the aforesaid Edwards Patent No. 1,521,514, is mounted on a suitable base 1, the latter providing a trunnion 2 for the swinging shear frame 3. Said shear frame 3 provides the usual opening 4 for the continuous passage therethrough of the rapidly moving rolled product 5 of the mill, which, travelling in the direction of the arrow A on

the usual conveyor rollers 6, 6, is to be cut up by the shear without interruption to its movement, into pieces of predetermined length.

5 Adjacent the opening 4, the shear frame 3 carries the usual fixed blade 7, arranged to cooperate with a movable blade 8 which is pivotally carried by a head 9 slidable in ways 10 of the swinging frame 3; according to the 10 usual arrangement, this head 9 is connected to the transverse pivot shaft 11 of the blade 8, as are also the upper ends of a pair of links 12, 12 (only one being shown), which are adapted to swing on a fixed trunnion 13 of 15 the base 1. Also pivotally attached to the transverse shaft 11 are a pair of connecting rods 14, 14 (only one being shown), the latter being connected to and operated from a reciprocating cross head 15, which is attached 20 to a shear-operating piston 16, contained in the steam cylinder, designated as a whole by the numeral 17, of my invention.

Fig. 2 shows the piston 16 in a position corresponding to the normal "at rest" position of the shear frame 3, as shown in Fig. 1, said piston 16 being then in close proximity to the upper cylinder head 18, through which passes the piston rod 19. As shown in Fig. 2, the cylinder 17 has associated therewith the inclosing casing 20 of a slide valve 21, hereinafter termed the main valve, which is mounted in a suitably ported sleeve 22 received in the bore of casing 20 and closed at its ends by the heads 23 and 24. Said 30 casing 20 provides a pair of steam inlet connections 25 and 26 and a single exhaust steam connection 27, all in constant communication with the interior of the lining sleeve 22. Through suitable registering ports in said 35 lining sleeve 22, communication of its interior is also adapted to be established with steam passages 28 and 29 opening into opposite ends of cylinder 17, and exhaust passages 30 and 31 opening into said cylinder 40 inwardly of and adjacent to the respective steam passages 28 and 29.

The main valve 21 provides two intermediate skirted piston portions 32 and 33, the former controlling, as hereinafter described, 45 the steam and exhaust passages 28 and 30, respectively, and the latter controlling, as hereinafter described, the steam and exhaust passages 29 and 31, respectively. Beyond and in spaced relation to the portion 32, said 50 main valve provides a guiding piston portion 34, whose movement in the sleeve 22 gives the effect substantially of a dash pot. At the opposite end, said main valve provides, in spaced relation to the portion 33, an operating piston portion 35, received in a large-diameter extension 36 of the sleeve 22.

The main valve portion 35 is the means by which the entire valve 21, with its several parts 32, 33 and 34, is shifted longitudinally 55 in the sleeve 22, to obtain the working and

return strokes of piston 16 within the cylinder. In the normal "at rest" position of the mechanism, as illustrated in Fig. 2, the main valve 21 occupies its extreme right hand position, owing to unbalanced steam pressure. 70 That is to say, while the portions 32 and 34, exposed to steam from inlet 25, balance each other, and while the portion 35, because of bleed opening 37 therein is also substantially balanced, nevertheless the portion 33 has steam pressure on its left-hand side and only atmospheric pressure on its right-hand side, and thus the steam pressure normally maintains the valve in the position shown by Fig. 2. The maintenance of pressure in the space 38 between the valve portion 35 and the head 24 is controlled by a pilot valve, the operation of which, as hereinafter described, 75 procures the steam-actuated movements of main valve 21. Said pilot valve and its appurtenant devices, which form no part of the present invention, may be of any suitable construction; as here shown by way of example, a rotary pilot valve of the type disclosed in the aforesaid Edwards patent may 80 be employed. To this end, as shown in Fig. 5, the main valve casing 20 has secured thereto on one side, in the vicinity of the space 38, a pilot valve casing 39, the bore of which, on an axis at right angle to that of the main valve casing bore, receives a rotary valve member 40. Communicating with and parallel to the bore of the pilot valve casing 39, are two pairs of diametrically opposite passages 41, 41 and 42, 42, the last named having 85 extensions 43, 43 that open into the space 38, as shown in Fig. 2. These extensions 43, 43 register with longitudinally extending recesses 44, 44 on the interior wall of the space 38, as also shown in Fig. 2.

The pilot valve 40 extends diametrically across the bore of its casing 39, and in the position shown in Fig. 6, it blanks off and closes the two passages 42, 42 that communicate with the space 38. Pilot valve 40 is 90 secured to the end of a valve stem 45, by the rotation of which said valve is carried into a succession of different positions, relative to the pairs of passages 41, 41 and 42, 42. That is to say, in the construction shown, the valve 95 40 is adapted to be moved, intermittently, through angles of forty-five degrees, in order first, to connect adjacent passages 41 and 42, and then, to blank off either pair of diametrically opposite passages,—repeating this operation for each operation of the shear.

For operating the pilot valve 40, any suitable mechanisms, such as the ratchet mechanisms of the aforesaid Edwards patent, or the pressure-controlled devices of the co-pending Fay and Dahlstrom application Serial No. 322,594, filed November 29, 1928, may be employed; such pilot valve operating mechanism forms of itself no part of my invention, and hence need not be shown or de-

scribed in detail herein. It is sufficient to note that each operative movement of the pilot valve 40, to initiate a cut of the shear, may be made responsive to the travel of the stock 5, and that each reset movement of the pilot valve 40 may be made responsive to the swing of the shear frame, all as fully described in the aforesaid Edwards patent, and as here shown schematically in Fig. 1. To this end, the stem 45 of valve 40 carries a ratchet wheel 46, whose teeth are adapted to be engaged by a pawl 46', which is pivotally carried at 47 by a bent lever 48, the latter being journalled loosely on the end 15 of valve stem 45. The free end of said lever 48 is connected by a link 49 with the trigger mechanism 50 of the shear, the latter providing a finger 51, depending from a rock shaft 52 which is connected by an arm 53 20 with the link 49. When the finger 51 is knocked upwardly by the front end of the stock 5, such movement is communicated by the linkage and ratchet mechanism to effect a forty-five degree movement of the valve 25 40, thus to carry it from the diagonal position of Fig. 6 (or any other diagonal position in which it is left) into either a vertical or horizontal position, as the case may be, thereby to establish communication between 30 adjacent passages 41 and 42, in consequence of which the cut of the shear is inaugurated, as hereinafter described.

When the pilot valve 40 moves through forty-five degrees into the broken line position of Fig. 6, the two passages 41, 41, which have a common exhaust outlet 54 to the atmosphere, procure, by their thus established communication with the passages 42, 42, a sudden release of the full steam pressure that prevails in the space 38. Thereupon, the valve 21 shifts sharply to the left, as shown in Fig. 3, because the right-hand side of portion 35 has a larger area than the left-hand side of portion 33; in consequence of this, the pressure normally effective to push the valve to the right is overcome, and the preponderance of pressure in the other direction, procures a movement to the left. With this left-hand shift of valve 21, its portion 33 45 uncovers the exhaust passage 31 and covers the inlet passage 29, as shown in Fig. 3; in this way, not only is the ingress of live steam from inlet 26 to the interior of the cylinder 17 cut off, but the steam then in said cylinder 50 on the left hand side of piston 16 undergoes an immediate drop in pressure, because of the connection established by passage 31 with the exhaust outlet 27. This left-hand movement of valve 21 also carries the valve portion 32 to a position where it covers the exhaust passage 30 and uncovers the inlet passage 28 at the upper end of the cylinder, so that the steam from inlet 25 exerts its full 55 pressure against the right-hand side of piston 16 to move the latter rapidly, as shown in

Fig. 3, for the operative stroke of the shear.

On this operative stroke, the pilot valve 40 is reset, by another movement through forty-five degrees, to block off the communication between the passages 41, 41 and 42, 42. This may be effected, as described in the aforesaid Edwards patent, by the movement of the shear frame 3 itself, which takes place, as above described, on the left hand stroke of piston 16, as shown in Fig. 3. The mechanism for thus resetting the pilot valve 40 forms no part of the present invention; said mechanism may be of the type shown and described in the aforesaid Fay and Dahlstrom application, or it may be, as shown in Fig. 1, of the character described in the aforesaid Edwards patent, and involving a ratchet wheel 55, on the valve stem 45, with which cooperates a slidable member 55' having a link connection 56 with a bell crank 57, the latter having a link 58 adapted for adjustable connection, as shown at 59, to the shear frame 3. When the latter makes its operative swing, the movement of member 55 imparts a forty-five degree movement to the pilot valve 40, to reset the latter in a position to blank off the pairs of passages 41, 41 and 42, 42 from each other; this movement of the pilot valve shuts off the space 38 from the exhaust outlet 54, and thereby causes the steam pressure to build up in the space 38 (owing to the bleed passage 37), so that the main valve 21 is quickly moved from the position of Fig. 3 to the position of Fig. 4, the latter being its normal position. With this movement of the main valve, the portion 32 thereof, as shown in Fig. 4, uncovers the exhaust passage 30 so as to connect the right hand end of cylinder 17 with the exhaust outlet 27; at the same time, the portion 33 of said main valve uncovers the inlet passage 29 and thereby allows the full pressure of steam from the inlet 26 to be exerted against the left hand side of piston 16, so as to produce a rapid return movement of said piston to the normal position shown in Fig. 2. In this way, the return stroke of the shear frame 3 is effected, the same as the operative stroke, by opening one end of the cylinder to exhaust, and by making the full steam pressure effective on the other side of the piston; in other words, for each complete cycle of operation of the shear frame, operative swing and return swing, there is simultaneously procured an admission of live steam against one side of the piston, and an exhaust of steam from the other side toward which the piston movement takes place. Thus the return swing of the shear frame may be made just as rapid and just as positive a movement as the operative swing.

Each of the exhaust passages 30 and 31 is provided with an adjustable valve 60, which may be manually set, as described in the aforesaid Edwards patent, to control the rate

at which the steam, from one end or the other of the cylinder, is exhausted, both on the operative and on the return strokes. In this way, the speed of the operative or cutting stroke of the shear may be definitely and accurately predetermined by the setting of the exhaust valve 60 in the passage 31,—this valve being set in a position which corresponds to the particular speed at which the material 5 is being delivered from the mill. In like manner, the other exhaust valve 60 in the passage 30 can be set to obtain any desired speed for the return stroke of the shear frame.

As the piston 16 nears the end of said return stroke, it moves over the inner end of exhaust passage 30. In consequence of this, the end of the return stroke is cushioned by the steam that is trapped at this time between 20 said piston and the cylinder head 18, since such steam, with passage 30 covered by the piston, has only the restricted entrance to said passage afforded by the shallow cylinder wall recess 30'. The piston 16 comes completely to rest at the end of the return stroke 25 since the valve mechanism, as above described, has already been returned to the position shown by Figs. 2 and 4, where the steam pressure through passage 28 is cut off. 30 In this rest position, which disposes the shear in readiness for taking its next cut, the full pressure of the steam supply 26 is transmitted to the interior of cylinder 17 through the passage 29; this steam pressure in the rest or 35 stationary position of the piston 16 becomes effective on both sides of said piston, due to the clearance or leakage space 17' provided between the piston and the wall of the cylinder 17. Consequently, upon the next-ensuing 40 movement of main valve 21, to exhaust steam from the lower or left hand side of the piston simultaneously with the admission of steam to the upper or right hand side of the piston, the resulting piston movement is not delayed by the necessity of building up steam pressure on the right hand side thereof, since the full steam pressure already prevails on 45 said right hand side.

I claim:

1. The combination with a swinging flying shear, of steam cylinder and piston actuating means therefor, to secure each cutting stroke of said shear and its return to open or rest position, valve means movable to initiate each cutting stroke of the shear by opening one end of said cylinder to steam pressure and the other to exhaust, and means responsive to the cutting stroke so initiated for shifting said valve means to open the first-named end of said cylinder to exhaust and the other to steam pressure, thereby to produce the return of said shear to normal rest or open position.

2. The combination with a swinging flying shear, of steam cylinder and piston actu-

ating means therefor, to secure each cutting stroke of said shear and its return to open or rest position, valve means movable to initiate each cutting stroke of the shear by opening one end of said cylinder to steam pressure 70 and the other to exhaust, means responsive to the cutting stroke so initiated for shifting said valve means to open the first-named end of said cylinder to exhaust and the other to steam pressure, thereby to produce the return of said shear to normal rest or open position, and means to adjust the exhaust openings from each end of said cylinder, thereby to control the speed of both the cutting 75 and the return strokes of said shear.

3. The combination with a swinging flying shear, of steam cylinder and piston actuating means therefor, to secure each cutting stroke of said shear and its return to open or rest position, a main steam valve movable to admit steam under pressure against one side of said piston and to exhaust steam from the other side, thereby to effect the cutting movement of said shear, a pilot valve movable to procure, by steam pressure, such movement of the main steam valve, means responsive to such cutting movement of the shear for resetting said pilot valve, and for procuring by steam pressure the return of said main steam valve to its normal position, 90 where it exhausts steam from the first-named side of said piston and admits steam to the other side, thereby returning the shear to its normal rest or open position.
